SEALED JOINT

Dean D. Crandell, Buffalo, N. Y., assignor to
National Gypsum Company, Buffalo, N. Y.

Application February 28, 1936, Serial No. 66,284

2 Claims. (Cl. 72—16)

This invention relates to an improvement in finishing wall and ceilings to produce a smooth and continuous surface, and particularly to a system for producing a covered joint between

5 adjacent panels forming a wall or ceiling that can be covered with a decorative coating of paint or paper without interposition of a cementitious coating such as lime or plaster.

Attempts have been made heretofore to construct walls or ceilings of panels without using a plastering finish prior to the final decorative coat. Thus it has been proposed to pack a cementitious filling material within the joint or open seam between the edges of adjacent wall board panels, but this does not yield an unmarked, smooth and continuous surface since there is contraction and expansion of the wall or ceiling with consequent opening up at the joint, with consequent rupture of the decorative film. The use of fabric tapes as a joint reinforcement has been found unsatisfactory since where a filler is used back of the tape this often cracks and falls or pulls away and, where there is no filler, breathing occurs with deposition of dust with the formation of unsightly marks following the joint. Reinforcements of wire mesh or perforated tape have been used to some extent but the mesh is generally too thick for use where a paper or paint finish is to be applied with a previous plaster coat. Where cloth fabrics have been used to tape wall board joints, it has been found that the cloth stretches in expansion and bulges upon return of the panels to the original position. Thin metal tapes perforated to form a mechanical key have been suggested, but must be used with a joint filler to have the proper binding or keying action and upon compression the filler is prone to crack and the perforated tape loosen.

40 In some cases unsightly joints are formed by the protrusion of the joint filler mechanical key through the perforations of the tape; if there is no protrusion the mechanical key may work away from the tape.

45 An object of the present invention is the provision of a smooth continuous surface covering the joint which will take a paint or paper decorative coating without the necessity of intermediate plastering, and a joint which possesses 50 a strength in excess of that possessed by the panels themselves so that rupture at the joint is eliminated.

Another object of the invention is the formation of a joint that will not breathe and show 55 a deposit of soot and dust along the line of the

joint with consequent discoloration of the decorative surface.

The accompanying drawing is a perspective view of the improved joint system.

In the application of the paper or cloth fabric joints used heretofore, the paper or fabric tape was glued to the edges of adjacent wall board either with or without a joint filler. Where joint filler was used, this filler is prone to crack and fall away and breathing occurs 10 through the paper or fabric tape at a rate different from the rest of the structure with discoloration. A further disadvantage of this fabric or paper tape joint system is the relative weakness thereof and the ease with which it can be 15 ruptured. As contrasted to the prior fabric tape joint capable of withstanding only about 20 pounds, the joint of the present invention will withstand 60-65 pounds or better. That is to say, the joint is stronger than the wall board 20 itself.

The unusual strength or reinforcement of the joint is obtained by the use of a cloth fabric tape of balloon cloth, a fabric cloth wherein the individual strands are made of tightly twisted fibers 25 and strands which are closely woven, as contrasted with the relative open weave of canvas tapes heretofore used.

Where heretofore cloth fabric tapes have been glued at their edges to adjacent wall board, in the present improved joint system the whole tape is saturated throughout with a strong, tough and elastic waterproof glue, such as casein glue, and this saturated tape applied to the edges of adjacent wall boards. As this dries a drum effect is 30 obtained, since there is a marked shrinking of the tape and glue which tightens up the joint. With good waterproof glues, such as the casein 35 glue mentioned, good elasticity is present in the glue so that the adjacent panels may move toward one another without bulging of the tape, and may move away from one another without rupture at the joint.

To produce the finish desired and to eliminate any suggestion of tape edge, a thin coating of casein cement is applied over the glue saturated tape and the whole sanded down. In the drawing wallboards 10 are shown attached to a supporting member or stud 11 by means of nails 12. A joint 13 is thus formed between the adjacent 50 wall boards and over this is placed tape 14 saturated in glue 15. The finish of the joint system is plastic casein cement 16 sanded to form tapered edges 17.

The bonding carrier of the finish cement 16 55

should be compatible with glue 15 so that there is fusion between the bonding element upon the tape and that in the finish, in order to get uniform elasticity throughout these elements.

5 The finished joint does not show a relative rate of breathing between the joint and the rest of the structure since the glue is substantially impermeable to air and moisture, and the joint system of this invention therefore prevents 10 coloration due to dust deposition filtered out of air passing through the wall or ceiling.

The term casein cement comprises a cement wherein casein is the body or carrier and throughout which there is a filler of finely ground mica 15 or other aggregate.

What is claimed is:

1. In a wall construction a supporting member, panels having edges attached to said supporting

member to form a wall board joint, a tape of finely woven fabric placed over said joint, said tape being attached to the edges of adjacent panels by means of an elastic glue substantially impermeable to air and moisture, said glue permeating 5 said tape throughout and a plastic cement finish over said tape.

2. In a wall construction a supporting member, panels having edges attached to said supporting member to form a wall board joint, a tape of finely woven fabric placed over said joint, said tape being attached to the edges of adjacent panels by means of an elastic glue substantially impermeable to air and moisture, said glue permeating said tape throughout and a plastic filler with a 10 bonding carrier of the same composition as the glue of said tape covering said tape.

DEAN D. CRANDELL.
